APPARATUS FOR USE IN THE FIRE CONTROL OF GUNS MOUNTED ON UNSTABLE PLATFORMS

John Percival Watson, Westminster, London, England, assignor to Vickers-Armstrongs Limited, Westminster, England, a British company

Application May 2, 1933, Serial No. 668,954
In Great Britain May 4, 1932

3 Claims. (Cl. 89—41)

This invention relates to apparatus for use in the fire control of guns mounted on a ship or other unstable platform where the errors in training or in training and elevation due to the 5 rolling or rocking and other movements of such platform have to be corrected. It has been proposed, for use with anti-aircraft guns, to provide means for correcting the angle of elevation or "site" of the target derived from a controlling or 10 "director" sight (which angle includes the disturbance due to the roll angle) for the vertical error due to the rolling or rocking of the platform and for comparing the corrected or "stabilized" elevation (or a function thereof) with the elevation angle (or a function thereof) produced by the calculator (which latter angle is 15 independent of the roll) so as to enable the setting of the latter to be kept properly adjusted. Similarly to provide means for correcting the 20 angle of training derived from the controlling sight for the lateral error due to the rolling or rocking of the platform and for comparing the corrected or "stabilized" training angle (or a function thereof) with the training angle (or a function thereof) produced by the calculator so 25 as to enable the latter to be kept properly adjusted. The uncorrected or "unstabilized" angles obtained from the controlling sight may be associated mechanically with the rolling or rocking corrections determined in any suitable manner and the resultant angles, which are the corrected or "stabilized" angles of elevation and training, may be indicated by means of pointers moving coaxially with other pointers which are 30 driven from the calculator in accordance with the angles of elevation and training produced thereby, the latter angles being termed the "generated" angles. By adjusting the setting portions of the calculator so as to cause the pointers operated thereby to move in synchronism with the first-mentioned pointers, the calculator will be 35 properly set for the given conditions at any moment. Alternatively either or each of the two sets of pointers may be replaced by a plotting device which makes two plots on a moving sheet or band of paper, one plot being in accordance with the corrected or "stabilized" angles received from the controlling sight and the other being in accordance with the generated angles. The calculator is then adjusted so as to cause the second plot to fall on the mean or smoothed path of the first-mentioned plot and in this manner inequalities in the transmission of the corrected or "stabilized" angles are smoothed out. Also are provided means for incorporating corrections due to 40 the different angular positions both in elevation and in training occupied at any moment by the controlling sight and the gun or guns due to vertical and lateral deflections applied to the latter. Furthermore are provided means whereby the 45 uncorrected or "unstabilized" angles of elevation and training obtained from the controlling sight have added to them various corrections herein-after referred to in order to determine the correct angles of gun elevation and gun training to be 50 transmitted to the gun or guns.

It has also been proposed to provide means for deriving from the calculator a movement in accordance with the roll in the normal vertical plane of the sight (herein termed the "sight roll") and for elevating or depressing the controlling sight in accordance with the said derived "sight roll" so that the sight elevating number is relieved of the work heretofore necessary in compensating for the "sight roll". One may 55 also add to the movement in accordance with the "sight roll" a movement in accordance with the elevation angle (or a function thereof) derived from the calculator, and also the correction for "sight elevation cross level", so that in this case 60 the only work required to be done by the sight elevating number is to vary the elevation when the rate of elevation of the target alters as shown by the target moving away from the sight line, the sight remaining on the target so long as this 65 rate does not vary.

One can also provide means for deriving from the calculator the required training correction due to the roll measured in a vertical plane at right angles to the normal vertical plane of the 70 sight, this roll being known as the "sight trunnion roll" and the said correction being known as the "sight training cross level", and for training the controlling sight in accordance with the said derived "sight training cross level". Thus the 75 sight training number is also relieved of the work heretofore necessary in correcting the training for the movement of the sight due to "sight trunnion roll". One may also add to the movement in accordance with the "sight trunnion cross level", 80 a movement in accordance with the training angle (or a function thereof) derived from the calculator so that in this case the only work required to be done by the sight training number is to vary the training when the rate of training or 85 bearing of the target varies as shown by the target moving away from the sight line, the sight remaining on the target so long as this rate does not vary. Furthermore the vertical and lateral deflection setting handles normally provided on 90

the calculator may be arranged at the controlling sight station, the movement of these latter handles being transmitted in any suitable manner to the corresponding shafts of the calculator. In this manner the necessity for the pairs of elevation and training pointers (or the plotting devices) mentioned in my U. S. Patent No. 1,891,397 and in concurrent U. S. application Serial No. 577,846 and the specifications of my English Patents Nos. 374,058 and 374,059, is avoided as the point of reference now becomes the actual target.

The chief object of the present invention is to simplify anti-aircraft fire control apparatus of the above type and adapt it for use with surface, or low-angle-of-fire, guns, such as ordinary naval guns or "torpedo defense guns", etc.

According to the present invention the apparatus comprises a gyroscopically stabilized member by which a device is operated in accordance with "gun trunnion roll", this device being used for deriving the "gun training cross level" and the "gun elevation cross level" corrections which are incorporated in the movements given to the gun training and gun elevation indicators or transmitters. In addition the said member may, if desired, operate two further devices, one in accordance with "sight roll" and the other in accordance with "gun roll". The "sight roll" device serves to impart the required elevational correction to the controlling or "director" sight and the "gun roll" device serves to impart the required elevational correction to the gun elevation indicator or transmitter. No provision is made for "sight training cross level" correction as this is not necessary owing to the low angles of sight elevation as compared with the angles obtaining in anti-aircraft gun fire control.

With these considerations in view, the invention resides in the concepts, and instrumentalities for embodying same described hereinbelow, defined in the subjoined claims, and illustrated in the accompanying drawing.

In the drawing:

45 Fig. 1 is a diagram of one embodiment, and Fig. 2 is a diagram of a modification.

1, 2 and 3 are three pick-up members associated with the aforesaid gyroscopically stabilized member which is in the form of a horizontal metal disc 4. The pick-up members 1 and 3 are mounted at right angles to each other and are supported by a carriage 5 which can be trained around the stabilized disc 4. The pick-up member 2 is supported on a separate carriage 6 which can also be trained around the disc. The carriage 5 supporting the pick-up members 1 and 3 is controlled by the pinion 9 which may receive movement from the calculator 8 proportional to gun training. By this means the pick-up member 1 is maintained at all times in a vertical plane parallel to a plane containing the axis of the gun trunnions. Under the separate or combined effects of rolling and rocking of the ship, and the consequent instability of the pick-up member 1 relative to the stabilized disc 4, the pick-up member will receive, due to its maintained contact with the disc, movement proportional to roll along the gun trunnions. This movement is applied through a relay 10 and power motor 11 to traverse two camoids or three dimensional cams 12 and 13. Both these camoids are rotated for gun elevation by a shaft 14 from the calculator 8. The camoid 12 is designed to operate a result member 15 which will receive move-

ment proportional to "gun training cross level". This movement is then applied through intermediate shafting to one element of a differential 16 a second element of which receives movement from the calculator 8 proportional to gun training. The movement of the result member of the differential is applied to a transmitter 17 controlling the transmission of training to the guns. 5

The carriage 6 supporting the pick-up member 2 is controlled by a pinion 7 which receives movement equivalent to sight training from the calculator 8. Due to this control, the pick-up member 2 is maintained in a vertical plane parallel to a plane containing the axis of the director sight. Under the separate or combined movements of rolling and rocking of the ship, the pick-up member 2 is unstable relative to the disc 4 and due to the maintained contact of the pick-up member with the disc, this member receives movement proportional to roll along the line of sight. This movement is applied to a relay 18 controlling a power motor 19 situate at the director sight A. The movement of the power motor is applied to one element of a differential 20 a second element of which is controlled by the 25 elevating hand-wheel 21 and the movement of the result element of this differential is applied to the elevating gear on the sight. The sight is therefore stabilized against all effects of rolling along the line of sight. 30

The pick-up member 3 mounted at right angles to the pick-up member 1 on the carriage 5 and controlled in training by the pinion 9, is maintained in a vertical plane parallel to a plane containing the axis of the gun barrel. It receives movement due to its instability relative to the stable disc 4, which movement is proportional to roll along the line of the gun. This movement is applied via a relay 22 and power motor 23 to one element of a differential 24; a second element of this differential is controlled by a quadrant 25 which receives movement from the aforesaid camoid 13. This camoid is rotated for gun elevation and traversed for gun trunnion roll and imparts movement to the quadrant 25 proportional to "gun elevation cross level". The result member of the last-mentioned differential therefore receives a movement which is proportional to "gun roll" $\pm$ "gun elevation cross level" and this total is applied to the differential 26. 50 At this differential, an amount proportional to gun elevation is added and the total is applied to the gun elevation transmitter 27.

From the foregoing it will be seen that the pick-up member 2 is displaced from the pick-up member 3 by an amount equal to the lateral deflection correction (i. e. sight training $\pm$ gun training).

In cases where lateral deflection is small, it may be found convenient to dispense with the pick-up member 2 measuring "roll along line of sight". For such a case movement proportional to "roll along the line of gun" obtained from the pick-up member 3 might be applied in the same way as indicated for the pick-up member 2 to approximately stabilize the sight against the effect of roll along the line of sight. An arrangement for carrying out this idea is shown in Fig. 2, in which the former pick-up member 2 of Fig. 1 is eliminated together with its concomitant appurtenances, and the relays 18 and 22 are both operated by pick-up 3. By these means, the member 3 is used to add corrections to the director sight, as postulated.

No details are given of the calculator 8 pro- 75

ducing lateral deflection, gun elevation and training, as this may take any of the usual forms employed for this purpose.

The aforesaid pick-up members may be constructed as described with reference to Figure 4 of the drawing relating to English Patent No. 374,058.

The expressions "sight roll", "gun roll", "gun trunnion roll", "gun elevation cross level", "gun training cross level" and "sight training cross level" are defined in the specification of my aforesaid English Patent No. 374,058.

What I claim and desire to secure by Letters Patent of the United States is:—

- 15 1. Apparatus for use in the fire control of low-angle-firing guns having trunnions and axes and mounted on an unstable platform, comprising a gyroscopically-stabilized member having a stable horizontal-plane; two pick-up members movable with the unstable platform and moved by said plane relatively to the platform in substantially vertical planes, respectively parallel to the gun trunnions and to the axis of the gun, so that each is moved according to the component of movement of the platform in its respective vertical

plane; means for deriving gun-training cross level and gun-elevation cross level corrections from that pick-up member which is movable in a plane parallel to the gun trunnions; and means for transmitting movement from the other pick-up member to the gun elevation indicator in accordance with roll along the line of the gun.

5 2. Apparatus as in claim 1, and including a director-sight and having a third pick-up member movable with the platform and engaging said plane so as to be moved by said plane in a substantially vertical plane parallel to the axis of the director sight, and means for transmitting movement from this pick-up member to the director-sight.

10 3. Apparatus as in claim 1, adapted for use where lateral deflection is small and including means for utilizing the movement of that pick-up which operates in a plane parallel to the axis of the gun both for imparting correctional movements to the director-sight and for imparting elevational corrections to the gun elevation transmitter.
